US0D1059311S

(12) **United States Design Patent** (10) Patent No.: **US D1,059,311 S**
(45) Date of Patent: ** Jan. 28, 2025

(54) **REACTION CHAMBER BASE PLATE**

(71) Applicant: **ASM IP Holding B.V.**, Almere (NL)

(72) Inventors: **Todd Dunn**, Cave Creek, AZ (US);
Abhishek Mangoli, Phoenix, AZ (US);
Ruchik Bhatt, Chandler, AZ (US)

(73) Assignee: **ASM IP Holding B.V.**, Almere (NL)

(**) Term: **15 Years**

(21) Appl. No.: **29/803,622**

(22) Filed: **Aug. 13, 2021**

(51) LOC (15) Cl. **13-03**

(52) U.S. Cl.

USPC **D13/182**

(57) **CLAIM**

The ornamental design for a reaction chamber base plate as shown and described.

DESCRIPTION

FIG. 1 is a front perspective view of the reaction chamber base plate, showing our new design;

FIG. 2 is a back perspective view thereof;

FIG. 3 is a front view thereof;

FIG. 4 is a back view thereof;

FIG. 5 is a right side view thereof;

FIG. 6 is a left side view thereof;

FIG. 7 is a top view thereof; and,

FIG. 8 is a bottom view thereof.

The broken lines in the figure drawings are included to show portions of the reaction chamber base plate that form no part of the claimed design.

1 Claim, 6 Drawing Sheets
